CLAIM

The ornamental design for a biological fluid collection device, as shown.

DESCRIPTION

FIG. 1 is a first perspective view of a biological fluid collection device showing our new design;

FIG. 2 is a second perspective view thereof;

FIG. 3 is an elevation end-view thereof;

FIG. 4 is a first side-elevation view thereof;

FIG. 5 is a second side-elevation view thereof;

FIG. 6 is a third side-elevation view thereof;

FIG. 7 is a fourth side-elevation view thereof; and,

FIG. 8 is a cross-sectional elevation end-view taken substantially along lines 8-8 of FIG. 4.

The portion of the biological fluid collection device depicted in broken lines forms no part of the claimed design.
